UNITED STATES PATENT OFFICE.

EDWARD C. CARRIS, OF WASHINGTON, IOWA, ASSIGNOR TO THE CARRIS MANUFACTURING COMPANY, OF WASHINGTON, IOWA.

BUTTON-BLANK-GRINDING MACHINE.

Application filed December 24, 1925. Serial No. 77,439.

The object of my invention is to provide a button blank grinding machine especially adapted for use in grinding blanks of irregular outline for forming them into discs circular in outline and of proper diameter for forming buttons.

Still a further object is to provide a machine wherein blanks of irregular outline will be fed in between spindles and then engaged and carried to position where the irregular blank will be ground for forming a button blank disk.

Still another object is to provide a positioning structure arranged to properly position the irregular blank, so that it may be properly engaged between a pair of spindles before it is carried to grinding position.

Still a further object is to provide a distributor mechanism for feeding a plurality of pairs of spindles from a single hopper.

Still a further object is to provide a machine having simple means for adjustment for thereby determining the diameter of the completed button blank.

Still a further object is to provide a machine wherein the irregular blanks will be fed to position and then adjusted so that when the blank is engaged between the pair of spindles, it will be in proper grinding position and will then be carried upwardly beyond the positioning structure at which time the spindles together with the blank will begin to revolve.

Still a further object is to provide a machine in which the mechanism is arranged at an angle of forty-five degrees to horizontal, so that the feeding of the blanks from the hopper to grinding position will be by gravity.

Still a further object is to provide a stationary block and a revolving disk for bringing the irregular blank into the best grinding position, wherein the largest possible button disk will be ground therefrom.

Still a further object is to provide a means for causing a constant spring pressure on the upper spindle so that the centered button blank will be securely held between the upper and lower spindle while being ground.

With these and other objects in view, my

invention consists in the construction, arrangement and combination of the various parts of my device, whereby the objects contemplated are attained, as hereinafter more fully set forth, pointed out in my claims, and illustrated in the accompanying drawings, 50 55

in which:

Figure 1 is an end view of my improved button blank grinding machine with part of the gear housing broken away and shown in section to better illustrate the construction there- 60

of.

Figure 2 is a plan view of the top of the machine looking in the direction of the arrow of Figure 1.

Figures 3 and 4 are details of the upper 65 ends of the upper spindles, Figure 4 being a view taken on the line 4—4 of Figure 3.

Figures 5 and 6 are details of the lower ends of the lower spindles, Figure 6 being a view taken on the line 6—6 of Figure 5. 70

Figure 7 is a sectional view taken on the line 7—7 of Figure 2, showing one set of spindles and the grinding element therefor.

Figure 8 is a sectional view on the line 8—8 of Figure 1 showing the feed plate and the 75 mechanism mounted thereon.

Figures 9 and 10 are diagrammatic views showing irregular blanks being properly positioned.

Figure 11 is a sectional view on the line 80 11—11 of Figure 1, showing the positions of the spindles relative to the grinding elements, as well as the chute for disposing of ground disks and dust.

Figure 12 is a diagrammatic view, showing 85 the engaging spindles in position where they are engaging the irregular blank.

Figure 13 is a diagrammatic view similar to Figure 12, showing the grinding position of the blank. 90

Figure 14 is a diagrammatic view similar to Figure 12, showing the ground button being released.

Figure 15 is a detail view of the blank en- 95 gaging ends of the spindles.

Figure 16 is a section on the line 16—16 of Figure 8 showing how the distributor arms are operated.

Figure 17 is a section on the line 17—17 of Figure 16, showing the guides for the distributor arms; and

Figure 18 is a detail sectional view taken on the line 18—18 of Figure 7 illustrating the driving mechanism of the lower spindles.

In the accompanying drawings, I have used the reference numeral 10 to indicate a pair of brackets which support the base plate 11 on which the various parts of my button grinding machine are mounted. The base plate 11 is supported at an angle as clearly shown in Figure 1.

A feed plate 12 is attached to the base plate 11 perpendicular thereto. The upper cam shaft brackets 13 and the lower cam shaft brackets 14 are also attached to the base plate 11, and the bracket 14 is secured to the supporting bracket 10.

Rotatably mounted in the brackets 13 is the upper cam shaft 15, and in the brackets 14 is the lower shaft 16.

A main drive shaft 17 is mounted in bearings 18 of the brackets 10. The shaft 17 is driven by a belt 19 on the drive pulley 20.

For driving the lower cam shaft 16, I provide a pulley 21 on the shaft 17.

A belt 22 transmits power to the pulley 23 on the shaft 24.

A pinion 25 on the shaft 24 is in mesh with the gear 26 on the stub shaft 26^a. A pinion 27 secured to the gear 26 is in mesh with the gear 28 on the lower cam shaft 16. Thus the lower cam shaft 16 is rotated at proper speed which is much slower than the main drive shaft 17.

Rotation can be imparted to the cam shafts at will by manipulating the belt shifter 43 which shifts the belt 22 to either the tight pulley 23 or loose pulley 23^a.

On the opposite end of the cam shaft 16 is a sprocket 29. On the cam shaft 15 is a similar sprocket 30. A chain 31 transmits power from the sprocket 29 to the sprocket 30. The two cam shafts thus rotate in unison at the same speed.

A pair of brackets 32 mounted on the base plate 11 have slidably mounted therein, emery wheel supporting frames 33. For driving the emery wheels 34, a pulley 35 is provided on the shaft of each one.

Mounted on a shaft 36 is a bevel gear 37 in mesh with another bevel gear 38 on the drive shaft 17. The upper end of the shaft 36 is rotatably mounted in a bearing 39 and a pulley 40 is secured to the end thereof. A belt 41 affords operative connection between the pulley 40 and the pulleys 35. An idler 42 is provided between the pulleys 35 and the belt 41 extends from the two pulleys 35 and over this idler.

From the foregoing, it will be seen that rotary motion can be imparted to the emery wheel 34 by the gears 38 and 37, shaft 36, pulley 40 and belt 41 on the pulleys 35, which

speed will be somewhat higher than that of the drive shaft 17.

The position of the emery wheel 34 may be varied by turning the screw 44, which is threaded into the boss 45 on the frame 33.

A lock nut 46 retains this adjustment.

This allows the grinding of buttons of various diameters as will hereinafter be more fully set forth.

Lower spindle.

As there are a plurality of spindles, I will describe but one.

The lower spindle 47 is slidably and rotatably mounted in bearings 48 on the plate 11. The upper end of the spindle 47 is milled as shown in Figure 15 for gripping the surface of a button blank. The lower end has a washer 49 secured thereto by means of a cap screw 50.

For sliding the spindle 47, I provide an arm 51 mounted between collars 53 on a stationary shaft 52.

An adjustment bar 54 is pivoted in the end of the arm 51 and is held in adjusted position by the opposing action of the adjusting screws 55 and 56.

The spindle 47 is operatively connected to the arm 51 by an engaging member 57 having the hooked ends 58, which engage the upper surface of the washer 49.

A cap screw 59 in the bar 54 rests against the cap screw 50. This construction allows free rotation of the spindle 47.

The member 57 is pivoted to the bar 54 and has a set screw 60 bearing thereagainst, which allows adjustment so that the cap screws 50 and 59 bear against each other at all times.

On the opposite end of the arm 51 is a roller 61 in contact with a cam 62, which contact is maintained by the weight of the spindle 47.

For insuring a positive return of the spindle 47, a return face 63 is provided on the cam 62.

The various positions of the spindle 47 are shown in Figures 7, 12, 13 and 14.

It is desirable to impart rotation to the spindle 47 before it reaches the emery wheel 34.

A shaft 64 journaled in bearings 64^a on the under side of the base plate is provided for this purpose and is operatively connected to the shaft 24 through the medium of pulleys 65 and 66 and the belt 67.

A spiral gear 68 on the shaft 64 is in mesh with a spiral gear 69 loosely mounted on the spindle 47 between the bearing 48 and a bifurcated member 70.

A finger 71 on the gear 69 extends down along the spindle 47, and through the bifurcated portion of the member 70.

An engagement member 72 is secured to the spindle 47. When the spindle 47 has been raised by the arm 51 until the member 72 en-

gages the finger 71, as shown by the dotted lines in Figure 18, the spindle will start rotating in unison with the gear 69.

Upper spindle.

The upper spindle 73 is slidably mounted in bearings 74 on the plate 11. The lower end of the spindle 73 has a hardened point 75 for engaging a button blank at its center of rotation.

For sliding the spindle 73, I provide an arm 76 pivoted on a shaft 77 between the ears of another arm 78.

The ears of the arm 78 are positioned between the collar 79 on the shaft 77. The arm 78 has a roller 80 thereon, which is held in contact with the cam 81 by a spring 82.

A set screw 84 on the arm 76 is held in contact with an extension 83 on the arm 78. The set screw 84 is used for adjusting the arm 76 relative to the arm 78.

The purpose of this construction will hereinafter be more fully set forth.

There is a spring 82 and a spring 85 for each arm 76 and 78, but I have not illustrated them all in some of the figures as they are duplicates.

The arm 76 is connected to the spindle 73 by a tongue 86, and groove 87 arrangement. The groove 87 is held against the tongue 86 by a spring 88.

This construction causes the spindle 73 to be lowered and raised by the arm 76 and at the same time prevents any tendency of the spindle 47 rotating the spindle 73. The spindle 73 is flattened at 89 for clearing the emery wheel 34.

Blank distributing mechanism.

It is desirable to have but one hopper on a machine and a plurality of spindles. This necessitates provision of a distributing mechanism for alternately feeding blanks from the hopper to the spindles. To accomplish this result, I have provided the following described mechanism.

A hopper 90 is secured to the feed plate 12 and is designed to receive the button blanks 91 to be ground.

A plate 92, having notches 93 on the periphery thereof, is rotatably mounted in the hopper 90 on a shaft 94.

A shaft 94^a is operatively connected to the lower cam shaft 16 by means of a bevel gear 95 on the shaft 16, which is in mesh with the bevel gear 96 on the shaft 94^a. The shaft 94^a is coupled to the shaft 94 by a break pin joint comprising the sleeves 97 and 98, which have perforated extensions through which a rod 99 as a common nail may be inserted.

The perforations may be lined with a hardened metal so that they will shear the pin 99 if the plate 92 should stick or bind.

It is readily apparent from the foregoing that rotation will be imparted to the

plate 92 whenever the cam shaft 16 is rotating. As the plate 92 rotates a blank 91 will fall into each notch 93 when said notch is passing beneath the pile of blanks in the hopper 90. The plate 92 is slightly thinner than the blanks 91 so that only one blank can lodge in each notch 93.

When the blank has reached the position A in Figure 8 it will leave the notch 93 by gravity and slide down the feed plate 12. In case dirt or a blank is lodged in the notch 93 so that it will not be discharged on to the feed plate 12, I provide openings 100 (Figure 8) and 101 (Figure 7) for allowing the dirt or blanks to fall through the machine on to the floor.

For distributing the blanks as they are discharged on to the feed plate 12, I provide distributor arms 102, 102^a, 102^b, and 102^c, which are slidably mounted in a block 103 on the feed plate 12. The arms 102 have extensions 104 which extend through the feed plate 12, are slidably mounted in a bracket 105 secured to the stationary shaft 52, and terminate in rollers 106.

The rollers 106 ride on the periphery of cams 107 which are secured to the lower cam shaft 16.

The cams 107 are so timed that a blank 91 will follow the path B (Figure 8) when all the distributing arms are down. It will follow the path C when 102 and 102^c are raised. It will follow the path D when 102, 102^a and 102^b are raised. It will follow the path E when 102^c only is down, in which case it first strikes the extension 108 of the arm 102^c.

The extension 108 has notches 109 for allowing free movement of the arms 102^a and 102^b.

Pockets 110 are formed at the lower ends of the distributing arms to receive the blanks 91 until the cams 107 raise them and release the blanks 91.

Blank positioning or gauging mechanism.

A positioning plate 111 is secured to the lower edge of the feed plate 12 and the surfaces of these plates are even, so that a blank 91 from the plate 12 may slide onto the plate 111. The lower spindle 47 projects through an opening 112 in the plate 111.

A positioning block 113 and a guide 114 are mounted on the plate 111. A positioning disc 114 is rotatably mounted on the plate 111. The disc 114 is secured to a shaft 115 mounted in bearings 116 on the plate 111. The shaft 115 is operatively connected to the shaft 64 by spiral gears 117 and 118 best shown in Figures 7 and 8 of the drawings.

The positioning mechanism just described functions in the following manner (Figures 9 and 10). Soon after the lower spindle is brought to position where the finger 71 and the engagement member 72 are engaged, and the spindle starts to revolve, a blank 91 is

released from the pocket 110 and slides onto the plate 111 and against the revolving disc 114 or against the guide 111^a. By the rotation of the disc 114, it is forced against the rotating spindle 47, both of which are turning in the same direction. The pressure on the bottom of the blank will be to the left and the pressure against the spindle will be upward and a blank of the shape shown in Figure 10 will usually be rotated until the flat sides are brought against the disc and spindle, and will be retained there until the top of the spindle 47 falls below the plate 111 when the blank 91 will slide into position against the block 113 (Figure 10). The rotation of the disc 114 causes the blanks to assume a position where the blank's center of gravity is closest to the center of the spindle. It may be mentioned that the blanks 91 are sometimes irregular in outline and it is desirable to bring two of their edges against the block 113 and disc 114 for crowding the button blank to position where it will completely cover the opening 112 in the plate 111. Assuming that the blank 91 is substantially of the outline, as shown in Figure 10, and has moved by gravity to the position shown in solid lines in that figure, then the button blank ground from the blank 91 would have its lower edge unfinished as this edge would not be within the grinding radius of the periphery of the emery wheel, and would not therefore be a good usable blank, unless it was re-ground and made into a blank of smaller diameter.

The revolving disc 114 will cause the blank 91 to rotate around because of the curved lower edge of the blank 91 and to be shifted until it is brought to position where its side edges, which are straight, will rest against the block 113 and disc 114, at which time the downwardly extending corner of the blank shown in dotted lines in Figure 10 will prevent further rotation of the blank which in such position will completely cover the opening 112 so that when the button blank is ground from the blank 91, it will be of the greatest possible diameter and will be perfect.

50 *Practical operation.*

The practical operation of my button blank grinding machine step by step is as follows:

The blanks, which are clam shells cut into squares or blanks are placed in the hopper 90. The clam shells are irregular in outline and have curved surfaces, so that the blanks 91 will be irregular in outline.

The blank 91 will be released from the pocket 110 and be positioned by the disk 114 over the opening 112. The relative position of the spindles is illustrated in Figure 7.

Figure 12, the cam 81 then causes the arm 76 to descend with the spindle 73 until the point 75 touches the blank 91. Further move-

ment of the arm 78 causes the extension 83 to leave the set screw 84, which causes the point 75 to be held against the blank 91 by the spring 85. The cam 62 then causes the arm 51 to ascend with the spindle 47, the end of which 70 engages the lower surface of the blank 91.

Figure 13, further rotation of the cams 81 and 62 cause both spindles to ascend in unison thereby keeping the pressure of the spring 85 equal throughout the ascension. 75

In other words, the extension 83 will remain equidistant from the set screw 84 throughout the axial movement on rise of the spindles and the button blank.

The spindle 47 will commence rotating before the blank 91 reaches the emery wheel 34 because of the engagement of the member 72 with the finger 71, which is constantly rotating whenever the machine is running and the shifter 43 is in proper position. This causes the blank 91 to rotate and be first ground by the slanting face of the emery wheel 34 and then finished by the flat face thereof. 80

Figure 14, the roller 80 engages the low spot 90 119 on the cam 81 which causes the extension 83 to engage the set screw 84, causing the spindle 73 to quickly rise to the position shown.

The ground blank 91^a then falls off the 95 lower spindle into the dust chute 120. In case the blank 91^a sticks to the point 75 of the spindle 73, it will be knocked off by striking the chute 120 as the spindle rises out of the opening 121 which is just large enough to 100 allow passage of the spindle 73.

A similar opening 122 is provided for the lower spindle 47 and is large enough to allow passage of an unground blank.

The spindle 47 then begins to quickly recede 105 due to the engagement of the retracting face 63 of the cam 62 and the roller 61 until it assumes the position shown in dotted lines in Figure 7. The upper spindle 73 follows it down and remains in a position above the 110 blank 91 while the blank is being positioned. This completes the cycle which occurs each time the cam shafts 15 and 16 rotate.

In the dust chute 120 are partitions 123, one for each spindle. The blanks 91^a, striking these partitions are precipitated toward the opening 124. A vacuum line and a separator may be attached to the opening 124 for separating the blanks 91^a from the dust as is usual in machines of a similar character. 115

Several of these machines may conveniently be set up to have a common drive shaft 17. The arrangement of the machine at an angle of substantially 45 degrees to the horizontal 125 permit the feeding of the blanks by gravity into proper centering position on the plate 111.

Adjustments.

The spindle 47 may be adjusted so that it 130

will carry a blank 91 just above the emery wheel 34 when in highest position, by manipulating the screws 55 and 56.

The tension of the spring 85 may be adjusted by the wing nut 125 for keeping the point 75 of the spindle 73 in contact with the center of the blank 91 and prevent its being dislodged from between the spindle 47 and 73 by the emery wheel.

10 The set screw 84 is used for adjusting the arm 76 relative to the arm 78 for keeping the extension 83 spaced therefrom during the ascension of the spindles and the grinding of the blank 91.

15 For making different sized button blanks the size of the block 113 and disk 114 may be changed so that they are farther away from the center of the opening 112.

20 The grinder 34 is then adjusted by the screw 44 to bring it also farther away from the opening 112.

For slight changes in the size of the button blanks produced, the emery wheel 34 only may be adjusted. For the larger sized 25 buttons, another spindle 47 may be substituted for the one which is shown, which has a larger reduced portion 126.

Some changes may be made in the construction and arrangement of the various parts 30 of my invention, without departing from the real spirit and purpose of my invention, and it is my intention to cover by my claims, any modified forms of structure or use of 35 mechanical equivalents, which may be reasonably included within their scope.

I claim as my invention:

1. A button blank grinding machine comprising a frame, a grinding element thereon, engaging means for bringing a button blank 40 into grinding position and means for centering the button blank on said engaging means before it is ground, said means for centering the button blank comprising a stationary block and a revolving disk.

45 2. A button blank grinding machine comprising a frame, a grinding element thereon longitudinally movable, spindles for carrying the button blanks into grinding position, centering means for the button blanks, said 50 centering means comprising an inclined plate for the blanks to slide on by gravity, a stationary block and a disk revolving toward said block, said block and disk being positioned on said plate to act as stops for said blanks as they slide down said plate, said disk in revolving causing the button blank to be crowded toward said block and in alignment with said spindles whereby it will be engaged by said spindles upon their longitudinal movement.

55 3. A button blank grinding structure comprising an inclined feed plate upon which the button blanks may slide by gravity, a 60 rotating grinding element spaced from the surface of said feed plate, a stationary block

and a disk mounted on said feed plate for serving as stops for the blanks as they are fed down said feed plate, said disk having one of its side faces positioned against said feed plate whereby the button blank engages the 70 peripheral face thereof upon being stopped by said disk, means for rotating said disk for moving said button blank over the surface of said feed plate until it engages said block whereafter rotation of said disk will 75 cause the blank to rotate to a centered position and means for engaging the blank after being so positioned and moving it to position to be ground by said grinding element.

4. In a button blank grinding machine, a 80 grinding element, a plurality of spindles for carrying blanks to grinding position, an automatic feeding mechanism for feeding blanks to each pair of spindles, said feeding mechanism comprising an inclined feed plate, 85 means for discharging blanks, one at a time, onto said feed plate at a predetermined position, a series of guide elements on said plate each adapted to guide a blank discharged on the plate when the guide element is resting 90 thereagainst, a pocket on the lower end of each guide element adapted to receive the blanks and means for raising said guide elements for successively discharging the blanks received in their pockets and a stationary block and a 95 revolving disk for positioning each blank before it is engaged between a pair of said spindles.

5. A button grinding machine of the character described comprising a grinding element, a pair of blank engaging spindles, means for moving said spindles longitudinally for engaging a blank and presenting it to the grinding element, said means comprising a two part arm having engaging portions, 105 spring means to hold said portions together and means for moving one of said arms so that the engaging portions are not in contact for thereby operating to maintain a substantially uniform resilient pressure of said spindles 110 on said blank while being moved from the positioning mechanism to the grinding element and while being ground thereby.

6. A button grinding machine of the character described comprising a grinding element, a button blank positioning mechanism, a pair of blank engaging spindles, means for moving said spindles longitudinally for engaging a blank after being positioned and presenting it to the grinding element, said 115 means comprising a two part arm having engaging portions, spring means to hold said portions together and means for moving one of said arms so that the engaging portions are not in contact for thereby operating to maintain a substantially uniform resilient pressure of said spindles 120 on said blank while being moved from the positioning mechanism to the grinding element and while being ground thereby, said means operating after 125 130

the blank is ground to relieve said tension due to said engaging portions again coming in contact with each other whereby positive movement of one of said spindles away from the other one occurs for releasing said blank.

7. A button grinding machine of the character described comprising a grinding element, a button blank positioning mechanism, a pair of blank engaging spindles for engaging a blank after being positioned and presenting it to the grinding element, an arm for operating one of said spindles for positive longitudinal movement, a two part arm for operating the other of said spindles for longitudinal movement the two parts of said arm having portions adapted to engage each other, means connecting the two parts of said arm whereby one may be moved relative to the other and means for resiliently constraining said parts when so moved, to position where said portions engage.

8. A button grinding machine of the character described comprising a grinding element, a pair of blank engaging spindles for engaging a blank and presenting it to the grinding element, an arm for operating one of said spindles for positive longitudinal movement, a two part arm for operating the other of said spindles for longitudinal movement, said two parts having engaging portions when said parts are in normal position with respect to each other, a spring connecting said parts together and means for causing said arms to be moved whereby said spindles will engage a button blank with said two parts of one of the arms being moved with relation to each other whereby said engaging portions are separated and said spring constrains said two parts toward their normal position with respect to each other and a substantially uniform pressure is maintained to hold the blank in position between said spindles.

9. A button blank grinding machine comprising a plurality of grinding elements, a button blank positioning mechanism for each grinding element, means for engaging said blanks after they are positioned by said mechanisms and moving them to grinding position, means for delivering blanks to said positioning mechanisms successively, said means comprising a guide element for each

mechanism, said guide elements being normally positioned in the path of travel of said blanks and means for successively moving certain of said guide elements out of said path to thereby leave one predetermined guide element to guide the blank to its respective positioning mechanism.

10. A button blank grinding machine comprising a plurality of grinding elements, a positioning mechanism for each grinding element, a pair of blank engaging spindles for each grinding element, means for moving said spindles longitudinally for engaging a blank and presenting it to the grinding element, said means operating to maintain a substantially uniform resilient pressure of said spindles on said blank while being moved from the positioning mechanism to the grinding element and while being ground thereby, said means comprising a pair of engaging members which are spaced from each other during the grinding operation and which engage each other for operating after the blank is ground to relieve said tension and positively move one of said spindles away from the other one and thereby release said blank.

11. A button blank grinding machine comprising a frame, a grinding element thereon, engaging means for bringing a button blank into grinding position and means for centering the button blank on said engaging means before it is ground, said centering means comprising a stationary block and a revolving disc having certain of their edges adapted to engage a blank, said edges being inclined with respect to each other for forming substantially a pocket to receive said blank.

12. In a machine of the class described, a feed plate, means for discharging blanks onto said plate, a plurality of guide elements terminating in pockets whereby a blank engaging one of said elements, will be guided into the pocket thereon and upon raising of said element said blank will be discharged from the pocket thereof to a predetermined position on the feed plate and means for successively raising said elements whereby but one of them can function as a guide for a blank being discharged onto the feed plate.

Des Moines, Iowa.

EDWARD C. CARRIS.
